No. 37,052.

Patented July 19, 1904.

UNITED STATES PATENT OFFICE.

ANDREW B. BUCHANAN, OF PEEKSKILL, NEW YORK.

DESIGN FOR OIL-CLOTH.

SPECIFICATION forming part of Design No. 37,052, dated July 19, 1904.

Application filed June 24, 1904. Serial No. 214,059. Term of patent 3½ years.

To all whom it may concern:

Be it known that I, ANDREW B. BUCHANAN, a citizen of the United States, and a resident of Peekskill, in the county of Westchester and State of New York, have invented a new, original, and ornamental Design for Oil-Cloth, reference being had to the accompanying drawing, in which the figure is a plan of an oil-cloth, showing my new design.

I claim as new and desire to secure by Letters Patent—

The ornamental design for oil-cloth herein shown.

ANDREW B. BUCHANAN.
